BEVEL SQUARE

Christie Thompson, Los Angeles, Calif.

Application February 3, 1931, Serial No. 513,214

6 Claims. (Cl. 33—91)

My invention relates to and has for a purpose the provision of a bevel square particularly adapted although not necessarily for use in roof framing or as a bevel or angle finder, and structurally characterized in such manner that in response to setting of an indicator to indicate a predetermined roof pitch, the device will automatically adjust to the angles corresponding to the correct plumb and side cuts to be taken on various classes of rafters in accordance with the indicated roof pitch, all to the end of greatly facilitating laying out of the work by eliminating mathematical computations and insuring accuracy in the work.

It is another purpose of my invention to provide a device of the above described character which will give an indication in terms of units of length such as the length of rafter required per running foot in accordance with the roof pitch to which the indicator is set so that the length of the rafter can be readily computed.

I will describe only one form of bevel square embodying my invention, and will then point out the novel features thereof in claims.

In the accompanying drawing:

Figure 1 is a view showing in front elevation one form of bevel square embodying my invention.

Figure 2 is a view of the bevel square in side elevation.

Figure 3 is a longitudinal sectional view taken on the line 3—3 of Figure 1 and looking in the direction of the arrows.

Figure 4 is a fragmentary of a portion of the bevel square in reverse side elevation.

Figure 5 is a transverse sectional view taken on the line 5—5 of Figure 3 and looking in the direction of the arrows.

Referring specifically to the drawing in which similar reference characters designate similar parts in each of the several views, my invention in its present embodiment comprises two members relatively adjustable angularly, one of the members constituting a stock S provided with a longitudinally extending recess 10, and the other member constituting a blade B pivotally mounted in the recess at one end of the stock by means of a pin 11 secured in the stock and a bushing 12 journaled on the pin and secured in the blade.

The bevel square also includes a pair of members in the form of blades B' and B² which are angularly adjustable oppositely relative to the stock S. To this end the blades B' and B² are pivotally mounted on the stock by means of a pin 13 constituting a common axis for the blades by which the latter are rendered angularly adjustable relative to the stock in a plane at a right angle to the plane of adjustment of the blade B.

The pin 13 extends freely through an opening in the stock into the recess 10 and terminates at its inner end in a ring 14 receiving the bushing 12 at one side of the blade B. The outer end of

the pin which extends through openings in the blades B' and B², is threaded at 15 to receive a nut 16 having a knurled head by which the nut can be readily turned. When loosened, the nut permits unrestricted pivotal movements of the several blades, whereas when tightened, the nut clamps the blades B' and B² against the stock by drawing the ring 14 into snug engagement with the bushing 12 and thus co-acts with the pin 13 to secure the blades in a selected position of adjustment.

An indicator I in the form of a cylindrical body 17 is slidably mounted in a bore 18 extending longitudinally in the stock S and communicating with the bottom of the recess 10. The body 17 is provided with a lateral projection 19 co-extensive in length with the body and working in a slot 20 extending longitudinally in the stock and communicating with the bore 18.

The body 17 of the indicator is provided with a lug 21 to which is pivotally connected at 22, one end of a link 23, the other end of which is pivotally connected at 24 to the blade B. From the body 17 also projects a pin 25 which extends through the slot 20 and has pivotally connected thereto one end of each of two links 26 and 27, the other ends of the links being pivotally connected at 28 and 29 to the blades B' and B² respectively as shown in Figure 1.

The indicator I broadly constitutes an actuator, and the links 23, 26 and 27 an operative connection between the indicator and the blades B, B' and B², by means of which actuation of the indicator will effect angular adjustment of the blades with respect to the stock, the blades B', B² being adjusted equally and oppositely with respect to the stock and in a predetermined proportion to the adjustment of the blade B. The lengths of the several links and the distances from the axes of the blades at which the links are connected to the blades, are such that with the indicator set to dispose the blade B at an angle corresponding to that of the correct angle for the plumb cut to be taken on a common rafter of an even pitched roof having a predetermined pitch, the blades B', B² will adjust to the angles corresponding to that of the correct side cut to be taken on the jack rafters. Likewise upon setting of the indicator to dispose the blade B at an angle corresponding to that of the correct plumb cut to be taken on hip and valley rafters, the blades B', B² will adjust to the angles corresponding to the correct right and left hand side cuts to be taken on these rafters.

To enable the indicator to be correctly set in accordance with different roof pitches, the projection 19 of the body 17 is disposed flush with the front surface of the stock S and is provided with a transverse index mark 30 (Figure 1) adapted to be aligned with the graduations of either

of two roof pitch scales 31 and 32 formed on the stock at opposite sides of the slot 20. The scales are graduated and numbered in inches rise per foot, the scale 31 being employed for common 5 rafters and the scale 32 for hip and valley rafters.

The graduations of the scales 31 and 32 are prolonged on opposite sides of the stock to provide other scales 33 and 34 respectively, the indicia of which designate the length per running 10 foot of rafters in accordance with the setting of the indicator with respect to the roof pitch scales 31 and 32.

The pin 25 is threaded on its free end at 35 and receives a thumb nut 36, which when tightened, 15 co-acts with washers 37 on the pin to clamp the indicator in a selected position of adjustment and thus co-acts with the nut 16 to secure the several blades in fixed positions.

It will thus be manifest that by setting the indicator to align its index mark 30 with the particular graduation on the scale 31 designating a predetermined roof pitch, that the blades B, B' and B² will angularly adjust to the respective positions wherein the angle of the blade B relative 25 to the stock will correspond to that of the plumb cut to be taken on a common rafter, whereas the angles of the blades B' and B² relative to the stock will correspond to those of the side cuts to be taken on the jack rafters. Also that upon 30 setting of the indicator to align its index mark 30 with the graduation on the scale 32 designating the predetermined roof pitch, that the blades will angularly adjust for the angle of the blade B to correspond with that of the plumb cut to 35 be taken on hip and valley rafters, and the angles of the blades B' and B² to correspond with those of the right and left hand side cuts to be taken on these classes of rafters. It will be understood however, that these angles will be correct only 40 for even pitched roofs.

Although I have herein shown and described only one form of bevel square embodying my invention, it is to be understood that various changes and modifications may be made therein 45 without departing from the spirit of the invention and the spirit and scope of the appended claims.

I claim:

1. An angle finder having a stock and a blade 50 angularly adjustable with respect to the stock, means for indicating roof pitches including an indicator movably mounted on the stock, means operatively connecting the indicator and blade by which actuation of the indicator to indicate a predetermined roof pitch will adjust the blade to 55 the angle of the plumb cut to be taken on a rafter for the indicated roof pitch, a second blade adjustable angularly with respect to the stock, and means operatively connecting the indicator and 60 second blade and by which actuation of the indicator to indicate said predetermined roof pitch will adjust the second blade to the angle of the side cut to be taken on the rafter.

2. An angle finder having two members angularly 65 adjustable with respect to each other, indicating means including an indicator movably mounted on one member, means operatively connecting the indicator and other member, and by which actuation of the indicator will adjust one 70 of the said members angularly to the other member, a third member angularly adjustable with respect to said one of the members in a plane at an angle relative to the plane of adjustment of

said two members, and means operatively connecting the indicator and third member and by which actuation of the indicator will angularly adjust the third member in a predetermined proportion relative to the adjustment of said other member. 5

3. An angle finder having a stock and a blade pivoted on the stock for adjustment angularly with respect to the stock, an indicator movably mounted on the stock, means operatively connecting the indicator and blade and by which actuation of the indicator will effect a predetermined adjustment of the blade, a second blade pivoted on the stock for adjustment angularly with respect to the stock, and in a plane at a right angle to the 15 plane of adjustment of the first blade, and means operatively connecting the indicator and second blade and by which actuation of the indicator will effect adjustment of the second blade in a predetermined proportion to the adjustment of the first 20 blade. 10

4. An angle finder having a stock and a blade pivoted on the stock for adjustment angularly with respect to the stock, an indicator slidably mounted in the stock for movement longitudinally of the latter, a link pivotally connecting the indicator and blade and by which actuation of the indicator will effect a predetermined angular adjustment of the blade, a pair of blades pivotally mounted on the stock for angular adjustment to 30 opposite sides of the stock, and links pivotally connecting the indicator and pair of blades and by which actuation of the indicator will effect equal adjustment of the pair of blades oppositely and in a predetermined proportion to the ad- 35 justment of the first blade. 25

5. An angle finder having a stock and a blade pivoted on the stock for adjustment angularly with respect to the stock, an indicator slidably mounted in the stock for movement longitudinally of the latter, a link pivotally connecting the indicator and blade and by which actuation of the indicator will effect a predetermined angular adjustment of the blade, a pair of blades pivotally mounted on the stock for angular adjustment to 40 opposite sides of the stock, links pivotally connecting the indicator and pair of blades and by which actuation of the indicator will effect equal adjustment of the pair of blades oppositely and in a predetermined proportion to the ad- 45 justment of the first blade, and means for securing the blades in selected positions of adjustment. 50

6. An angle finder comprising two members angularly adjustable relatively, roof pitch indicating means including a movable indicator, means whereby actuation of the indicator to indicate a predetermined roof pitch will adjust the members relatively to the angle of the plumb cut to be taken on a rafter in accordance with the indicated roof pitch, a pair of members angularly adjustable oppositely with respect to one of said two members, and means whereby actuation of the indicator to indicate said predetermined roof pitch will equally adjust the pair of members oppositely so that the angle formed by one of the said pair of members and said one of the two members will conform to the angle of the side cut to be taken on the 60 rafter. 60
